US0D1086942S

(12) **United States Design Patent** (10) **Patent No.:** **US D1,086,942 S**
(45) **Date of Patent:** **** Aug. 5, 2025**

(54) **VEHICLE CAB AND HOOD**

(71) Applicant: **Oshkosh Defense, LLC**, Oshkosh, WI (US)

(72) Inventors: **Jesse Gander**, Oshkosh, WI (US); **Devon Palmer**, Oshkosh, WI (US); **McCall Groen**, Oshkosh, WI (US)

(73) Assignee: **Oshkosh Defense, LLC**, Oshkosh, WI (US)

(**) Term: **15 Years**

(21) Appl. No.: **29/883,594**

(22) Filed: **Jan. 31, 2023**

Related U.S. Application Data

(60) Continuation of application No. 29/706,547, filed on Sep. 20, 2019, now Pat. No. Des. 980,118, which is a division of application No. 29/602,245, filed on Apr. 28, 2017, now Pat. No. Des. 864,031.

(51) **LOC (15) Cl.** **12-08**

(74) *Attorney, Agent, or Firm* — Foley & Lardner LLP

(57) **CLAIM**

The ornamental design for a vehicle cab and hood as shown and described.

DESCRIPTION

FIG. 1 is a front perspective view of the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing is included for the purpose of illustrating portions of the “article” and forms no part of the claimed design.

1 Claim, 6 Drawing Sheets
